[57] CLAIM

The ornamental design for a combined medical instruments case and sterilizer, as shown.

DESCRIPTION

FIG. 1 is a right perspective view of a combined medical instruments case and sterilizer, showing my new design;

FIG. 2 is a front elevational view thereof, the rear elevational view being identical;

FIG. 3 is a right end elevational view thereof;

FIG. 4 is a left end elevational view thereof;

FIG. 5 is a top plan view thereof; and

FIG. 6 is a bottom plan view thereof.

FIG. 1

FIG. 2

FIG. 3

FIG. 4

FIG. 5

FIG. 6
